(57) **CLAIM**

The ornamental design for a band, as shown and described.

DESCRIPTION

FIG. 1 is a bottom front perspective view of a band showing our new design;

FIG. 2 is a bottom rear perspective view thereof;

FIG. 3 is a front view thereof;

FIG. 4 is a rear view thereof;

FIG. 5 is a left side view thereof;

FIG. 6 is a right side view thereof;

FIG. 7 is a top view thereof;

FIG. 8 is a bottom view thereof; and,

FIG. 9 is a perspective view thereof showing the band in an environment in which it may be used.

The broken lines in FIG. 9 show environment that forms no part of the claimed design.

Primary Examiner — Jennifer Rivard**Assistant Examiner** — Melanie Pellegrini(74) **Attorney, Agent, or Firm** — Sterne, Kessler, Goldstein & Fox P.L.L.C.(57) **CLAIM**

The ornamental design for a band, as shown and described.

DESCRIPTION

FIG. 1 is a bottom front perspective view of a band showing our new design;

FIG. 2 is a bottom rear perspective view thereto;

FIG. 3 is a front view thereof;

FIG. 4 is a rear view thereof;

FIG. 5 is a left side view thereof;

FIG. 6 is a right side view thereof;

FIG. 7 is a top view thereof;

FIG. 8 is a bottom view thereof; and,

FIG. 9 is a perspective view thereof showing the band in an environment in which it may be used.
The broken lines in FIG. 9 show environment that forms no part of the claimed design.
